ATTORNEY.

UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 28,961, dated June 28, 1898.

Application filed June 1, 1898. Serial No. 682,299. Term of patent 31 years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing, making a part of the same.

The leading feature of my design is clearly shown in the accompanying drawing, which drawing shows only one-quarter of the full

design. The three-quarters not shown is of same configuration as the part that is shown. 15

A indicates the center panel, B the outer panel, and C the border.

Having as above fully described my invention, what I claim as new, and desire to secure by Letters Patent, is—

The design for a woven fabric, as shown and described.

W. T. SMITH.
